Application May 31, 1955, Serial No. 36,295

Term of patent 7 years

(Cl. D42—8)

FIG. 1.

FIG. 2.

FIG. 3.

FIG. 4.

FIG. 5.

Fig. 1 is a plan view of a watch case showing my new design;

Fig. 2 is a side view of the watch case;

Fig. 3 is a partial and vertically transverse section taken along the line 3—3 of Fig. 1;

Fig. 4 is a horizontally transverse section taken along line 4—4 of Fig. 1; and

Fig. 5 is a longitudinal section through the side of one end of the watch case and taken along the line 5—5 of Fig. 2.

The essential features of the design reside in the portion of the watch case shown in full lines. The dotted line portions showing the watch strap are for illustrative purposes only.

I claim:

The ornamental design for a watch case, as shown and described.
